Atty.

UNITED STATES PATENT OFFICE.

FREDRICK M. CONLEE, OF MADISON, WISCONSIN, ASSIGNOR TO NORTHERN ELECTRICAL MANUFACTURING COMPANY, A CORPORATION OF WISCONSIN

BRUSH-HOLDER FOR DYNAMO-ELECTRIC MACHINES.

SPECIFICATION forming part of Letters Patent No. 779,265, dated January 3, 1905

Application filed May 21, 1904. Serial No. 209,032.

To all whom it may concern:

Be it known that I, FREDRICK M. CONLEE, a citizen of the United States, residing at Madison, in the county of Dane and State of Wisconsin, have invented certain new and useful Improvements in Brush-Holders for Dynamo-Electric Machines, of which the following is a specification.

The object of my present invention is the production of a brush-holder which is reliable in operation, is simple in construction and contains a minimum number of parts, and is comparatively inexpensive to manufacture.

In the preferred form of my invention the brush-holder consists, essentially, of a single piece or strap of spring conducting metal, such as copper or brass, which is looped about the brush-holder stud or supporting-post and has the brush secured to its ends, means being provided for detachably clamping the looped portions to the stud.

The various features of novelty which characterize my invention are pointed out with particularity in the claims annexed to and forming a part of this specification. For a better understanding of my invention, however, reference may be had to the accompanying drawings and description, in which I have illustrated and described embodiments of my invention.

Of the drawings, Figure 1 is a perspective view illustrating a brush-holder clamped to its supporting-stud and carrying a brush. Fig. 2 is a perspective view showing the bent strap forming the brush-holder frame. Fig. 3 is an elevation showing a portion of a modified construction; and Fig. 4 is a view similar to Fig. 3, showing another modification.

In the drawings, 1 represents a suitable supporting stud or post, which is shown in Fig. 1 as cylindrical.

2 represents a strip, strap, or ribbon of some conductive resilient metal, such as tempered wrought copper or brass, doubled upon itself and having a portion 3 looped around the stud 1. The two end or leg portions 4

and 5 of the strap or ribbon 2 extend substantially side by side, but diverge slightly from each other as the distance from the stud increases. The ends 6 and 7 of the legs 4 and 5 are inturned or bent toward each other substantially at right angles to the main portions of the legs.

The brush 8, supported by the brush-holder, may be of any desirable construction, and is preferably formed of carbon. This brush is clamped against the outer face of the end portion 7 of the leg 5 by a bolt 9, which passes through apertures 7' and 6' in the portions 7 and 6, respectively, and is threaded into a nut 10, located between the legs 4 and 5, and preferably proportioned so as to be prevented from rotation by its engagement with the inner sides of the legs. A bolt 11 passes through the legs 4 and 5 adjacent the stud 1 and is threaded into a nut 12. The bolt 11 and nut 12 serve as a means for detachably clamping the brush-holder in any desired position. A washer member 13, located between the bolt-head and the leg 4, and space member 14, located between the legs 4 and 5, may be employed, if desired, though one or both of these members may be dispensed with. By unscrewing the bolt 11 the brush-holder may be adjusted angularly about the stud 1 to any desired position. It will be readily understood by those skilled in the art that the resiliency of the arms 4 and 5 serves to yieldingly hold the brush 8 against a coöperating commutator or collector ring, &c., with the proper amount of force.

Various modifications may be made in the form of my invention without departing from its spirit. For instance, instead of making the brush-holder frame as shown in Fig. 1 the portion 3 and stud or support 1 may be shaped as shown in Fig. 3 at 3' and 1', respectively, and secured in place by a bolt 11' passing through the stud and the legs 4 and 5, or the stud-engaging portion of the strap 2 may consist of two parallel portions bent together, as shown in Fig. 4 at 3'', in which case they

may also be secured to the stud by a bolt 11" passing through the two portions and the stud.

Other modifications in form and arrangement may be made without departing from the spirit of my invention.

What I claim as new, and desire to secure by Letters Patent of the United States, is—

1. In combination, a supporting stud or post, a strap of resilient conducting material looped about said stud or post, and a brush rigidly secured to the ends of said strap.
2. A brush-holder frame comprising a bent strap, a brush secured to the ends of said strap, and means for securing said strap to a support in such manner that the strap may be angularly adjusted with respect to said support.
3. A brush-holder frame comprising a single piece or strap doubled upon itself, a brush carried by the ends of said strap, and means for securing the body of said strap to a supporting stud or post.
4. A brush-holder comprising a pair of flexible legs integrally connected together, means for securing a brush to the ends of said legs, and means for securing the legs to a support at a point where the legs are connected together.
5. In combination, a strap or ribbon of resilient material doubled upon itself, means for securing a brush to the ends of said strap or

ribbon, and means for securing said strap to a support.

6. In combination, a strap or ribbon of resilient conducting material shaped to form a support-engaging portion and a pair of legs, 35 and means for securing a brush to the ends of said legs.

7. A brush-holder frame comprising a strap or ribbon of resilient conducting material doubled upon itself to form two legs extending 40 side by side, the ends of said legs being in-turned to form parallel portions, and a brush secured against one side of one of said in-turned portions by a bolt passing through both of the in-turned portions.

8. A brush-holder comprising a pair of legs of resilient material extending side by side and having portions at their ends bent toward one another forming two portions side by side, a brush resting against the outer surface of one of said portions, and means for securing the brush and the two in-turned portions rigidly together.

In witness whereof I have hereunto set my hand this 17th day of May, 1904.

FREDRICK M. CONLEE.
